UNITED STATES PATENT OFFICE

CARL A. PALMGREN, OF CHICAGO, ILLINOIS, ASSIGNOR TO PALMGREN STAPLING DEVICES, INCORPORATED, OF CHICAGO, ILLINOIS, A CORPORATION OF ILLINOIS

STAPLING DEVICE

Application filed June 24, 1927. Serial No. 201,132.

The invention relates to stapling devices in which it is formed like and used similar to an ordinary hand-hammer, and wherein staples may be fed under and driven by the hammer-head as each blow is struck or at the will of the operator; and the objects of the improvement are; first, to provide a staple driving tool of rapid operation, convenient to handle and facilitate the driving of staples; 10 second, to facilitate feeding of staples under the hammer-head as each blow is struck or at the will of the operator; third, to provide means for charging a number of staples in the form of a strip or cartridge within the device, 15 and means for feeding continuously into position successive staples for being driven at the will of the operator.

I accomplish the above said objects by making use of the novel form of construction 20 of a staple driving hammer as shown in the accompanying drawings, in which Figure 1, is a vertical side view of the exterior of the device showing the method of securing the handle portions to the hammer housing together with the thumb trigger shown in normal position; Figure 2, a vertical sectional view taken on the center line and showing the working parts in normal position; Figure 3, a vertical cross section thru the hammer housing and guide sleeve showing one of the locking lugs engaging the hammer housing to prevent turning; Figure 4, a sectional plan view showing a staple in position between the driver guides ready to be cut off 25 and driven together with the next succeeding staple in position for folding, and taken on line 4-4 of Fig. 2; Figure 5, a plan sectional view taken on line 5-5 of Fig. 2 looking down upon a part of the feeding mechanism; Figure 6, a cross sectional view taken 30 on line 6-6 of Fig. 2 showing the construction of the staple holding channel together with an end view of the thumb trigger and its spring for returning it to normal position 40 after feeding operation; Figure 7, a plan view taken on line 7-7 of Fig. 2 showing the retaining spring for holding staple in vertical position while being driven; Figure 8, a fragmental view taken on line 8-8 of Fig. 2 45 showing the driver together with the folding

furcations in raised position ready for cutting off, driving and folding the next succeeding staple; Figure 9, a similar view as to that of Fig. 8, but, after the staple has been driven and the next succeeding staple 55 folded.

In the drawings Fig. 1 shows the method of fastening the two handle members 10 and 10' to the hammer housing 11 by means of the rivets 12-12 and 13; and at the lower 60 end of 11 is shown a staple or tack pulling prong as at 14 which is formed in and a part of the housing 11, and at 15 is shown the thumb trigger in raised position. In Fig. 2 the hammer 16 is shown with its driver 17 and its folding furcations 18-18 and its return spring 19. At 20 is shown an internal sleeve for the purpose of supporting the spring 19 and also for providing a guide to prevent the hammer and driver from shifting out of proper alignment by making use of the slots 20' into which are engaged the side wings 17' that operate with the hammer 16, and in turn the sleeve 20 engages the housing 11 preventing its shifting by making use of the two lugs 20'', one of which is shown in Fig. 3 butting against the end wall of slot at the bottom of the housing as at 11'; this slot being machined across the bottom of the housing 11 for the purpose of receiving the feeding end of the staple channel as shown in Fig. 4 at 21, the top web 22 extending in to the center line as at 22'' for the purpose of forming a hold-down for making use of the last staple at the end of a strip, while the flaps 22' are stopped short to bear down upon the retaining spring 23 as shown at 24 in Fig. 2, and Fig. 7 while the bottom flanges of the handle members 10 and 10' rest upon the lip 25 and butt against the end of spring 23 for holding it in place. In the lower end of housing 11 are the openings 26-27-28 for the purpose of providing a guide for each leg of the staple while being driven by the driver passing down thru the opening 26 while the folding furcations 18-18 close down over the anvil 29 bending downward the legs of the next succeeding staple as shown in Fig. 8 at 30 and 31 and entering the openings 27 and 28. The housing 11 being made of a suit- 55 65 70 75 80 85 90 95 100

able material for hardening the top edge of the anvil 29 is hardened and sharpened for the purpose of providing a shearing edge as at 29' for shearing off the staples as the driver 17, which is made also of hardened material and has a cutting edge, passes down thru the opening 26 functioning as a shear and driver.

The hammer 16 is maintained up in normal position as shown in Fig. 2, by means of the 10 spring 19 acting against the shoulder 32 which in turn butts against the screw cap 33. To prevent the hammer head 16 from moving downward against the action of the 15 spring 19, as the tool is being raised for striking a blow, the pawl 34 engages the abutting face 35 formed in the side of the hammer 16 as a catch. This pawl 34 is connected by its lower arm to the feeding rod 36 that is operated by the thumb trigger 15 which is actuated by being pressed downward after the hammer has been raised into position for striking a blow releasing the hammer head 16 and allowing the feeding pawl 38 to be 20 forced inward by action of the spring 37 feeding the folded staple under the driver 17. As a blow is struck for driving a staple, the heel of the hammer housing 11 is stopped by coming in contact with the material to be 25 fastened, as shown at 39 Fig. 8, and due to the kinetic energy of the hammer-head it will continue downward forcing the driver to shear off the prepared staple and drive it thru the material 39 and into the fastening 30 material 40 overcoming the force of the spring 19, also pressing down and forming the next succeeding staple as at 30-31 of Fig. 9 by the action of the folding furcations 18-18 bending the prongs or legs down over 35 the anvil 29. After the staple has been driven the spring 19 will force the hammer head 16 up and back against the cap 33; the catch 35 will be in alignment to permit the pawl 34 to drop back into place being actuated by the 40 force of spring 41 thru the rod 36. As the pawl 34 rocks back into normal position the abutting face 42 formed as a part of 34 will abut with the face 43 a part of the arm 44 forcing the arm 44 to swing back retracting the 45 feeding pawl 38 for engaging the next succeeding staple; it being apparent of course that the spring 37 must have sufficient strength only to drag the strip of staples thru the channel 22 and that the spring 41 mounted 50 upon the pin 45 together with trigger 15 must have sufficient strength to actuate the members 34-44 upon the pin 13 and still overcome the strength of spring 37 to retract the pawl 38 to engage another staple thru the 55 opening 46 provided in the web of the channel 22 for allowing pawl 38 to engage the staples for feeding.

The principal use for which this type of stapling hammer is applicable will be for 60 tacking on shipping tags, card board posters

and for other use where light tacking is required so as not to damage the material being tacked on, and for this reason the spring 19 should have just sufficient strength to raise the hammer head 16 back up and against the stop cap 33 so that as light a blow possible with sufficient force to shear off and drive the staple will be required.

What I claim is—

1. A hand-hammer stapling device having a handle thereon, a reciprocating member having a staple-driving part and furcations behind said part to engage and bend the tips of a section of staple forming material into staple form, an anvil over which said sections are formed into staple form by cooperation of said furcations, a feeding pawl, and a manually operated means for operating said pawl to feed said sections into driving position.

2. A stapling device having a handle thereon for the purpose of using as an ordinary hand hammer, a reciprocating member having a staple-driving part and furcations behind said part to engage and bend the tips of a section of staple forming material into staple form, an anvil over which said sections are formed into staple form by cooperation of said furcations, a spring for maintaining said reciprocating member in normal position, and a manually operated feeding mechanism for feeding said sections into position for driving.

3. A stapling device having a handle thereon for the purpose of using said device as an ordinary hand hammer, a reciprocating member having a staple-driving part and furcations behind said part to engage and bend the tips of a section of staple forming material into staple form, an anvil over which said sections are formed into staple form, a spring for maintaining said reciprocating member in normal position, a retaining pawl for holding said reciprocating member in normal position during the up stroke for the striking of a blow, a feeding pawl actuated by said retaining pawl, a trigger manually operated for actuating said retaining pawl and said feeding pawl, and a spring actuating said feeding pawl inward for the feeding of said section to the position for driving.

4. In the combination of a stapling device, a handle for said device similar to a hand hammer, a hollow head on said handle, a reciprocating member within said hollow head having a staple-driving part and furcations behind said part to engage and bend the tips of a section of staple forming material into staple form, an anvil over which said sections are formed into staple form by cooperation of said furcations with said anvil, a spring for maintaining said reciprocating member in normal position, a retaining pawl for holding said reciprocating member in re-

tracted position during the up stroke of the device for the striking of a blow, a feeding pawl actuated by said retaining pawl during retraction for engaging the staple sections, a 5 spring for actuating said feeding pawl for feeding said sections into driving position, a manually operated means for actuating said retaining pawl, and a track for guiding said stapling material to said anvil.
